UNITED STATES PATENT OFFICE.

HENRY M. SHEER, OF QUINCY, ILLINOIS.

BURNER FOR OIL-HEATING SYSTEMS.

1,427,704.

Specification of Letters Patent. Patented Aug. 29, 1922.

Application filed June 15, 1921. Serial No. 477,761.

To all whom it may concern:

Be it known that I, HENRY M. SHEER, a resident of Quincy, county of Adams and State of Illinois, a citizen of the United States, have invented certain new and useful Improvements in Burners for Oil-Heating Systems, of which the following is a specification.

This invention relates to burners for oil heating systems, being particularly adapted for use in heating systems for brooders, incubators, and the like.

The object of the invention is to construct a highly efficient burner, wherein the several parts may be readily disassembled for cleaning.

Another object is to eliminate, as far as possible, the accumulation of carbon in the burner and in the oil feed thereto.

Another object is to provide means whereby the air being mixed with the flames may be regulated.

Another object is to arrange in the top of the support for the burner a well or the like, which acts primarily as a sight-feed, whereby the operator may determine the level of his oil at any time, and by the removal of the cap of the support, a wire may be injected in the feed-pipe for cleaning.

In the accompanying drawings:

Fig. 1 is a vertical section through the burner and support;

Fig. 2 is a top plan view thereof;

Fig. 3 is a bottom plan view; and

Fig. 4 is a transverse section through the burner.

The letter A, indicates the support, and B, the burner. The support preferably consists of a base 1 having a hollow upright portion 2 extending upwardly therefrom, somewhat enlarged at its upper end forming an oil chamber 3, being provided with a removable transparent cap 4, whereby the level of the oil within the oil chamber may be ascertained.

The numeral 5 indicates the base of the burner B, provided with a central opening 6, and an annular oil groove 7, into which leads the feed-pipe 8 extending horizontally from oil-chamber 3. This feed-pipe is preferably provided with a central duct 9, which communicates with a well 10, the latter being in communication with the annular oil groove 7. The purpose of this is to decrease the possibility of carbon forming at the discharge end of the feed-pipe 8, as

would likely happen should the end of the feed-pipe extend inwardly and flush with the outer wall of the annular groove 7. The oil passing through the feed-pipe into the well does not become fully vaporized, that is not vaporized to that extent where it will deposit carbon. A little carbon may form in the wall, but this will be instantly carried into the burner.

Furthermore, in this construction, the cap 4 may be removed, and a wire inserted into the duct 9, thereby eliminating the necessity of disassembling the parts when in the act of cleaning the feed-pipe. Arranged within the annular groove 7 is a suitable wick 11. Mounted directly above the wick and adapted to rest upon the base 5 are two cylinders 12 and 13, provided with a plurality of openings 15 which permit air to enter the chamber 14 directly above the wick from the inner chamber 15 and the chamber 16 formed by the upwardly-converging shell 17 arranged around the outer cylinder 13. The innermost chamber is provided at each upper end with a flanged deflector 18, preferably provided with a plurality of openings 19. These openings 19 are, however, adapted to be controlled by a vertically adjustable damper 20, whereby the air passing in through the inner cylinder may be regulated. The arrangement of the damper is such that the air passing out of the opening 19 is deflected horizontally to the flame as it extends above the deflector. The several cylinders are connected together by suitable fastening means, such as transverse rods or cotter-pins 21, 21, passing diametrically through the cylinder at right-angles to each other. These pins are readily removable, should it be desirable to renew any of the several parts.

As a means for rigidly securing the upper portion of the burner to the burner base, I preferably provide on the burner base a set of diametrically-disposed outwardly flanged segments 22, 22, beneath which is received locks 23, 23, extending inwardly from the shell 17, whereby by rotating the cylinders slightly they are locked permanently. The numeral 24 indicates a bail by which the burner can be turned and lifted from the burner base.

It will thus be seen that I have constructed a burner which is highly efficient, consisting of comparatively few parts, arranged in such a manner as to be most com-

pact, and connected in such a way as to be readily disassembled for cleaning.

I claim:

1. A burner comprising a base provided with an annular oil groove, means for admitting fuel thereto, spaced perforated cylinders surrounding said annular groove and extending upwardly therefrom, a deflector-cap closing the upper end of the inner cylinder and having holes therethrough, adjustable means for regulating the outlet of air through said holes in the cylinder and a shell surrounding the outer perforated cylinder.

15 2. A burner comprising a base provided with a central opening, an annular oil groove, means for admitting fuel thereto, spaced perforated cylinders surrounding said annular groove, and extending upwardly therefrom, a deflector-cap provided with openings adapted to close the upper end of the inner cylinder, means for regulating the outlet through the said openings, and an upwardly-converging shell surrounding the outer perforated shell.

30 3. A burner comprising a base provided with a central opening, an annular oil groove, means for admitting fuel thereto, spaced perforated cylinders surrounding said annular groove, and extending upwardly therefrom, a deflector-cap provided with openings adapted to close the upper end of the inner cylinder, means for regulating the outlet through the said openings, 35 an upwardly-converging shell surrounding the outer perforated shell, and means for detachably securing the upper portion of the burner to the base.

40 4. A fuel burner comprising a burner base having a control opening, an annular groove arranged concentrically with the opening, an oil well communicating with said annular groove, an air-deflector, means arranged above said annular oil groove, a hollow support for said burner base, and a feed pipe leading from said hollow support to the oil well adjacent said annular oil groove.

45 5. A fuel burner comprising a burner base having a cylindrical opening and an annular oil groove surrounding said opening, spaced perforated cylinders surrounding said annular oil groove, a deflector-cap for the inner perforated cylinder, a converging shell surrounding the outer perforated cylinder and hollow support for said burner base, a feed pipe arranged horizontally therebetween having a restricted opening therethrough arranged in horizontal alignment with the bottom of the oil groove.

60 6. A fuel burner comprising a base hav-

ing a central opening and an annular oil groove surrounding said opening, a well in communication with said annular groove, spaced perforated cylinders surrounding said annular groove, a deflector-cap provided with openings adapted to receive the upper end of the inner perforated cylinder, a damper for said openings, a converging shell surrounding the outer perforated cylinder, means for securing the shell and cylinder together, means for securing the shell to the burner base, a hollow support for said burner base, and an oil feed extending horizontally from said hollow support communicating with the well adjacent said annular groove, whereby oil may be fed to the groove.

65 7. A burner comprising a base provided with an annular groove, means for admitting fuel thereto, spaced perforated cylinders surrounding said annular groove and extending upwardly therefrom, a deflector-cap for the inner cylinder, a shell surrounding the outer cylinder, means for securing the cylinders and shell together, means for detachably securing the shell to the base, and a bail attached to the shell.

80 8. A burner comprising a base provided with a central opening, an annular groove arranged concentrically with the opening, an oil well communicating with said annular groove, an oil feed pipe entering the burner at right-angles thereto, and communicating with the oil well, the opening in said pipe being below the bottom of the oil groove, and a mixing-chamber arranged above the oil groove.

85 9. A burner comprising a base provided with a central opening, an annular groove arranged concentrically with the opening, an oil feed-pipe entering the burner at right-angles thereto, and communicating with said annular groove, the opening in said pipe being below the bottom of the oil groove, and a mixing-chamber arranged above the oil groove.

100 10. A fuel burner comprising a burner base having a control opening, an annular groove arranged concentrically with the opening, an oil well communicating with said annular groove, a hollow support for said burner base, a feed-pipe leading from said hollow support, and entering the burner at right-angles to the annular groove, and in communication therewith, 110 and a mixing-chamber arranged above said oil groove.

115 In testimony whereof I hereunto affix my signature.

HENRY M. SHEER.
